METHOD AND APPARATUS FOR TRANSPORTING FINELY DIVIDED SOLIDS

Lauritz E. Mylting, Ardmore, Pa., assignor to The Allen-Sherman-Hoff Company, Philadelphia, Pa., a corporation of Pennsylvania

Application May 8, 1952, Serial No. 286,687

7 Claims. (Cl. 302—25)

This invention relates to the art of handling finely divided solids and, more particularly, to removing finely divided ash from hoppers in power plants.

A general object of the invention is the provision of an ejector for entraining finely divided solids in a stream of air which will be relatively free from wear due to the passage of the solids through the ejector.

An object of the invention is the provision of a new method of and new apparatus for pumping dust-like materials by entraining the finely divided materials in a stream of air.

An object of the invention is the provision of a new steam ejector which may be utilized for entraining finely divided solids in a stream of air and which will obviate wear upon the steam nozzle due to impingement of particles upon the nozzle.

In removing finely divided ashes from hoppers in power plants and the like, it is known to utilize a system in which a partial vacuum is created in a conduit associated with the hopper to remove very finely divided dust or ash from the hopper. This partial vacuum is created by pumping air from the conduit so that the particles of dust or ash may be drawn through the conduit and discharged into separators or the like for disposal of the ash.

In one such type of ash-removal system, a steam ejector is utilized for drawing the air from the conduit and for the subsequent entrainment and discharge of the particles. Such an arrangement has many advantages for the accomplishment of the intended purpose but encounters the difficulty that the impingement of particles upon the parts of the ejector causes a very rapid erosion and wearing away of certain portions of the ejector and particularly of the nozzle used for forming the steam jet. Further, it has been found that as the wear of the nozzle increases, the efficiency of such ejectors drops very rapidly.

The present invention proposes a novel method of handling such fine particles of dust and ashes and a novel steam ejector for use in the practice of the method. In accordance with the method, the entrainment of the particles of dust or ashes and transport through the conduit system is accomplished by a flow of air induced by directing a jet of steam axially into a venturi tube. The airborne particles are guided, however, in a path spirally about the nozzle which is utilized to form the jet of steam rather than directly into the entrance portion of the tube itself. The spiral path of the airborne particles about the nozzle is such that there is a relatively gradual convergence of the stream of particles toward the body of the nozzle and the particles are carried into the mouth of the tube without striking the nozzle.

The apparatus of the invention comprises particularly an ejector including a casing having front and rear walls upon which the venturi tube and the nozzle respectively, are mounted; and an intake for receiving the airborne dust or ashes. The casing converges circumferentially about the nozzle from the intake toward the discharge

2

opening to produce a spiral motion of the airborne particles about the nozzle and into the discharge opening.

The invention will be more clearly understood by reference to the following detailed description and claims, taken in connection with the accompanying drawings, in which:

Fig. 1 is a schematic representation of an ash removal system incorporating the present invention;

Fig. 2 is a side elevation view of the ejector of the invention shown partly in cut away;

Fig. 3 is a view of the nozzle support and the nozzle;

Fig. 4 is a bottom view of the ejector of Fig. 2;

Fig. 5 is a sectional view of the casing of the ejector taken in the direction 5—5 of Fig. 2; and

Fig. 6 is a transverse sectional view of the casing of the ejector taken in the direction 6—6 of Fig. 4.

Referring now to Fig. 1, the ash removal system includes a number of hoppers 10, each normally associated with a furnace and each provided with a dust valve 11. A conduit 12 connects the dust valves 11 to an ejector 13 which, in accordance with the invention, serves as a means for transporting the dust from the valves 11 to a separator 14 through an outlet conduit 15. The ejector 13 is supplied with steam from a boiler 16 through a conduit 17.

Referring now to Fig. 2, one form of the ejector 13 of the invention is shown and includes a casing 18, a discharge conduit 19, a nozzle support member 20 and a nozzle 21. The casing 18 includes a front wall 22 incorporating a flange 23 for the support of the outlet conduit 19 and a rear wall 24 incorporating a flange 25 to which the nozzle support member 20 is secured.

The discharge conduit 19 forms a venturi tube having an inlet section 26, a throat section 27 and an outlet section 28, the opening 29 of the venturi tube being formed with convergent, cylindrical and divergent portions in the respective sections. At the entrance end of the conduit 19, a tapered portion 30 forms a continuation of an outlet opening 31 formed in the front wall 22 of the casing and connects that opening with the opening 29 of the conduit 19.

The nozzle support member 20 includes a reduced cylindrical portion 32 fitted into an opening 33 in the rear wall 24 of the casing 18. The reduced portion 32 is internally threaded at 34 to receive a threaded end portion of the nozzle 21. Openings 35 and 36 conduct steam to the nozzle from the steam conduit which may be connected to the support member 20 at a threaded entrance portion 37. The nozzle 21 is formed with an elongated body extending transversely through the casing and includes a tip 38 suitable for the formation of a jet of steam, as is known in the art.

The casing 18 may be connected to an inlet conduit, such as the conduit 12 in Fig. 1, through an intake 39 of the casing. The intake 39 has a circular cross section of suitable area and a flange 40 is provided for securing the associated conduit members to the casing.

In accordance with the invention, the casing 18 determines a flow of the airborne finely divided particles of dust or ashes and the like, from the inlet portion 39 of the casing, spirally about the nozzle 21, and into the opening 31. As shown particularly in Fig. 5, the body of the casing includes a peripheral portion 41 which is disposed circumferentially about the nozzle 21. This peripheral portion of the casing is spaced from the nozzle a distance which diminishes progressively from the inlet portion 39 to the terminal or discharge portion of the casing, designated generally at 42. The arc of the curve described by the casing may be of a spiraline nature, as for example the involute of a circle, suitable for producing a flow converging radially toward the opening 31. As shown particularly in Fig. 6, the front wall 22 may be

substantially normal to the transverse axis of the casing, e. g. the axis of the nozzle 21, while the rear wall 24 is tapered toward the front wall from the inlet portion 39 to the discharge portion 42. This tapered or converging arrangement assists in producing an axial component of flow toward the outlet opening 31. The casing, therefore, produces a vertical flow from the intake 39 into the discharge opening 31 in the front wall of the casing.

In operation, steam from the boiler 16 passes through the support member 20, the nozzle 21 and the tip 38 and through the opening 31 into the tapered portion 39 of the entrance section 26 of the venturi tube. The passage of the steam through the venturi draws air from the conduit 12 through the intake portion 39 through the casing 18 and into the conduit 19. As the air is withdrawn, a partial vacuum is formed in the conduit 12, thus drawing ashes from the hoppers 10 into the conduits. The particles are then drawn with the air through the conduit and into the casing wherein they follow a spiral path about the nozzle 21 under the influence of the peripheral portion 41 of the casing. As the particles approach the nozzle, they are drawn between the nozzle tip 38 and the walls of the opening 31 and into the opening 29 of the conduit 19. The stream of steam and airborne particles are then discharged into the separator 14.

It is to be understood that the specific nature of the present disclosure is not intended to be restrictive or confining and that various rearrangements of the parts and modifications of design may be resorted to without departing from the scope or spirit of the invention as herein claimed.

What is claimed is:

1. A steam ejector comprising a venturi tube having an entrance section including an opening, a nozzle directed into the opening and along the longitudinal axis of the said venturi tube, and a casing disposed about the nozzle and comprising an inlet and a periphery, the radial spacing between the periphery of the casing and the nozzle diminishing from the spacing at the inlet circumferentially about the nozzle.

2. A steam ejector comprising a venturi tube having an entrance section including an opening, a nozzle directed into the opening and along the longitudinal axis of the said venturi tube, and a casing disposed about the nozzle and comprising an inlet and a periphery, the radial spacing between the periphery of the casing and the nozzle diminishing from the inlet circumferentially about the nozzle and the rear wall tapering toward the front wall.

3. An ejector comprising a casing having front, rear and peripheral walls defining a flow-directing chamber and a substantially cylindrical wall defining an intake passage into said chamber, the front wall having an outlet opening, and a nozzle extending through the rear wall and into said chamber for directing a jet of fluid under pressure approximately normal to the front wall and through said opening, the axis of the intake passage opening into said chamber being laterally offset from the axis of the nozzle, the peripheral wall extending spirally about the nozzle and connecting the portions of the cylindrical wall adjacent to and remote from said outlet opening.

4. An ejector comprising a casing having front, rear and peripheral walls defining a flow-directing chamber and a substantially cylindrical wall defining an intake passage into said chamber, the front wall having an outlet opening, and a nozzle extending through the rear wall and into said chamber for directing a jet of fluid under pressure approximately normal to the front wall and through said opening, the intake passage opening into said chamber being laterally offset from the axis of the nozzle, the peripheral wall extending spirally about the nozzle and connecting the portions of the cylindrical wall adjacent to and remote from said outlet opening, the inner surface of the rear wall being inclined at a small angle to the inner surface of the front wall to crowd toward the outlet opening the fluid entering the casing through said intake passage.

5. An ejector comprising a casing having front, rear and peripheral walls defining a flow-directing chamber and a substantially cylindrical wall defining an intake passage into said chamber, the front wall having an outlet opening, and a nozzle extending through the rear wall and into said chamber and positioned with its axis approximately coaxial with said outlet opening for directing a jet of fluid under pressure approximately normal to the front wall and through said opening, the intake passage opening into said chamber being laterally offset from the axis of the nozzle, the peripheral wall extending spirally about the nozzle and connecting the portions of the cylindrical wall adjacent to and remote from said outlet opening.

6. An ejector comprising a casing having front, rear and peripheral walls defining a flow-directing chamber and a substantially cylindrical wall defining an intake passage into said chamber, the front wall having an outlet opening, a nozzle support member in an opening in the rear wall, and a nozzle extending through said member and into said chamber with its axis substantially coaxial with said outlet opening, the intake passage opening into said chamber being laterally offset from the axis of the nozzle, the peripheral wall extending spirally about the nozzle and connecting the portions of the cylindrical wall adjacent to and remote from said outlet opening.

7. An ejector comprising a casing having front, rear and peripheral walls defining a flow-directing chamber and a substantially cylindrical wall defining an intake passage into said chamber, the front wall having an outlet opening, and a nozzle extending through the rear wall and into said chamber for directing a jet of fluid under pressure approximately normal to the front wall and through said opening, the intake passage opening into said chamber being laterally offset from the axis of the nozzle, the peripheral wall extending spirally about the nozzle and connecting the portions of the cylindrical wall adjacent to and remote from said outlet opening, and a venturi tube secured to the casing and forming a continuation of said outlet opening.
